UNITED STATES PATENT OFFICE

2,065,967

AMALGAMATOR FOR THE RECOVERY
OF GOLD

Allan J. Clark and Warren H. Todd, Lead, S. Dak.

Application March 28, 1935, Serial No. 13,523

2 Claims. (Cl. 209—42)

The present invention relates to improvements in amalgamators for the recovery of gold and resides in certain improvements over our prior Patent 1,894,159 granted January 10, 1933.

In common with the objects and purposes of the prior device illustrated and described in our patent aforesaid, the present invention aims further to increase the yield by providing a construction which will require that the course of flow of the pulp be changed at right angles a greater number of times thus further inducing precipitation and amalgamation.

A further object of the invention is to provide in addition to the dilution water a backwash, discharged at higher pressure through several nozzles directed against the stream as it starts its flow from the first box whereby to check the speed of flow and afford opportunity for the settling out of the heavy amalgam.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a perspective view of an improved amalgamator constructed in accordance with the present invention.

Figure 2 is a top plan view of the same.

Figure 3 is a vertical section taken on the line 3—3 in Figure 2.

Figure 4 is also a vertical section taken on the line 4—4 in Figure 2.

Figure 5 is a similar view taken on the line 5—5 also in Figure 2.

Figure 6 is a vertical section taken on the line 6—6 in Figure 2.

Figure 7 is a side elevation of the apparatus, and

Figure 8 is a top plan view with the covers removed.

Referring more particularly to the drawings, 11 represents the discharge from a rod mill or the like whereby the thick pulp which is a mixture of ground ore particles with water, to which mercury has been added, is caused to discharge into the improved amalgamator. Such thick pulp is directed by the discharge 11 on to a screen or perforated plate 12. This screen 12 may be supported in any desired manner, preferably for ready removal, as upon the upper edges of the walls of the tray 13. The tray 13 rests removably in the pulp box or first launder 14. A horizontal delivery pipe 15 for dilution water is placed at one

end of the pulp box 14 and below the screen 12 therein, this pipe having a slot 16 directed substantially horizontally into the tray 13. This delivery pipe is connected to a supply pipe 17 to introduce a supply of water.

At the other end of the tray 13 and facing the distributing pipe 15 is a pressure distributing pipe 18 having a number of nozzles 19 connected therewith and projecting substantially horizontally into the tray 13 and directed opposite to the flow of water out through the slot 16. The pressure distributing pipe 18 is connected by a supply pipe 20 with a source of water or other fluid under higher pressure than the pipe 17; or these pipes may be connected both to the city or other water supply, in which case the pipe 17 will be made of greater diameter than the pipe 20 thus causing higher pressure in the distributing pipe 18 and nozzles 19.

As shown in Figures 1 and 5, the tray 13, 20 which is an amalgam tray, is provided with a lip or weir 21 at one end thereof which projects through a cut-away portion 22 in the adjacent end wall of the pulp box 14 and extends also through the cut-away portion 23 of the adjacent 25 wall of an amalgam tray 24 disposed in the second launder 25. This second launder is disposed at an inclination as shown in Figure 6 from a high point at its receiving end down to a low point at its discharging end where its inner side wall is 30 formed with a weir or lip structure 40 extending through a cut-away portion 41 in the inner wall of the second launder. This lip fits over an out-turned lip 26 on the inner adjacent wall of an amalgam tray 27 in the third launder 28. The 35 lip 26 is lower than the other walls of the tray 27 and forms a weir over which the pulp may overflow into the third launder, which third launder is also inclined as indicated in Figure 4.

The lower end of the tray 27 and its launder 28 40 discharge into a fourth launder 29 over a weir 30 shown in Figure 4. The fourth launder 29 extends at an inclination down beneath the second launder.

The discharge from the third launder 28 to the 45 fourth launder 29 is through an opening 43. The openings 22, 41 and 43 may be all in the same wall 44, which wall is common to the first, second, third and fourth launders and forms part of the weir 30 between the third and fourth launders. The 50 fourth launder may have an amalgam plate 42 therein.

It will be apparent that the first launder is at right angles to the second launder, the second launder at right angles to the third launder and 55

the fourth launder at right angles to the third launder. Accordingly the flow coming in the delivery pipe 11 is required to turn at right angles in the first launder 14 in order to flow over the 5 weir 21; it is then required a second time to change its course at right angles before flowing down the long expanse of the second launder 25 which is an elongated launder. When arriving 10 at the lower end of the second launder the flow must again change its course at 90° in order to flow into the third launder 28, and a fourth right angle turn is made when the pulp flows over the weir 30 and into the fourth or last launder 29. Thus the course of the flow of the pulp makes 15 four right-angled turns and passes through four boxes instead of three. At each right angle turn the rate of flow is checked so that ample time is allowed for precipitation and amalgamation. The arrangement of the four boxes is compact and 20 such as to enable the device to be contained within small compass. This is of value in that the same may be constructed as a unit for removably mounting upon a carriage or stationary frame such that the entire unit, comprising 25 all four boxes, may be lifted off the foundation or carriage and transported to a clean-out room.

The carriage or foundation is shown generally at 31 in Figure 7. Preferably a flat bottom 32 is provided for the entire unit extending beneath 30 all boxes to enable this device to seat readily in the frame or carriage 31. Lugs 33 are provided on the unit to receive lifting tackle. It is proposed to lift the whole device with a crane and to convey it to a guarded clean-up room before it is 35 unlocked. Over the various launders are protective screens 45 secured in place by padlocks or other means 44 which may be removed after the device is in the guarded clean-up room.

In Figure 8 removable riffles 34 and 35 are 40 shown in certain of the boxes. In applying the invention to a larger mill it was necessary to enlarge the compartments in proportion to the tonnage. In so doing even distribution of pulp in these wider boxes was difficult and was finally accomplished by placing removable riffles 34 and 35 45 in two of them, as shown in this Figure 8. It is not necessary to attach the riffles to the boxes and their height may be varied to control the rate of flow. These riffles will also settle out some 50 amalgam.

The dilution water comes in through the pipe 15 which introduces a flow of water in the direction of flow of the pulp through the device. Thus the rate of flow of pulp tends to be increased 55 by the introduction of the dilution water.

To check this, backwash water through the pipe 18 and nozzles 19 is introduced at a higher pressure in order to offset any increase in flow

rate. The backwash is in direct opposition to the movement of the pulp out of the first launder into the second launder and affords opportunity for settling out of the heavy amalgam even in the first launder. High pressures are not necessary 5 in the backwash but some pressure is desirable to effect a quick momentary checking of the flow. The chip basket in the discharge end of the grinding mill, as employed in our prior patent, has been replaced by the single screen 12 or perforated 10 plate, which covers the whole of the first compartment.

The compact arrangement of the device is facilitated by arranging the second and third launders in parallelism, with the first and fourth in 15 parallelism with one another, the first and fourth partially overlapping and the fourth extending beneath the sloping bottom of the long second launder.

It will be understood that the various launders 20 contain, or may contain, removable trays, or containers of copper or other amalgamable metal. These trays may be of any desirable depth.

It will be obvious that various changes may be made in the construction, combination and arrangement of parts which could be used without departing from the spirit of our invention and we do not mean to limit the invention to such details except as particularly pointed out in the claims.

Having thus described our invention what we 30 claim and desire to secure by Letters Patent of the United States is:

1. In an apparatus for the recovery of gold, a plurality of launders arranged angularly in sequence to receive the pulp, means for introducing the pulp to the launder first in series, a slotted pipe at one end of the launder in connection with a source of water supply for introducing dilution water in a direction the same as that of the pulp flow to the second launder, and a high pressure 40 pipe having a plurality of nozzles opposed to the slot and in communication with a source of higher pressure water for checking the rate of the flow of the pulp to the second launder. 45

2. In an apparatus for the recovery of gold, a plurality of launders arranged angularly in sequence to receive the pulp, means for introducing the pulp to the launder first in series, means for supplying dilution water to the first launder in the direction of flow of pulp to the second launder, and means opposed to said water supplying means for introducing water under pressure to said first launder in a direction opposed to the flow of said pulp and dilution water to check the rate of flow of pulp to the second launder. 55
